UNITED STATES PATENT OFFICE.

JOHN JEREMIAH, OF MERTHYR TYDFIL, ENGLAND.

GAME REGISTER AND TIMER.

1,315,728.

Specification of Letters Patent. Patented Sept. 9, 1919.

Application filed January 18, 1919. Serial No. 271,807.

To all whom it may concern:

Be it known that I, JOHN JEREMIAH, subject of the King of Great Britain, residing at Merthyr Tydfil, Glamorgan, England, 5 have invented new and useful Improvements in Game Registers and Timers, of which the following is a specification.

This invention relates to an appliance for registering and timing the simultaneous 10 progress of a plurality of games of billiards or bagatelle whereby an attendant can keep a register of the times which have been occupied in the simultaneous progress of a plurality of games of billiards at the several 15 tables in a billiard saloon, the object of the invention being to provide a rotating perforated disk adapted to carry one or more rods or pegs bearing marks indicative of the table or description of the game being played and automatically drop them at the end of a specified period in a manner to produce an aural indication of the termination 20 of the game.

The accompanying drawing illustrates the 25 apparatus whereby the invention can be performed.

In this drawing:—

Figure 1 is a perspective view of the appliance with its lids open. 30 Fig. 2 is a plan view of the appliance, the lids being closed.

Fig. 3 is a view similar to Fig. 2, with one of the lids removed to show the interior construction.

Fig. 4 is a vertical sectional view, parts being in elevation.

Fig. 5 is a detail plan view of the fixed plate.

Fig. 6 is a perspective view of two of the 40 pegs.

In these figures, A is a compound disk shown constructed in duplicated plates which, with an intervening distance piece, is mounted to undergo uniform angular rotation, as by clock-mechanism for example, it being for this purpose carried in the manner of the minute hand of a clock, for which hand the disk is substituted.

The disk is perforated by a plurality of 50 rings of small apertures a^1 a^2 a^3 adapted to receive and carry vertically situated short rods or pegs, the apertures a^2 being larger than the apertures a^1 and a^3 .

The rods or pegs are supported on a fixed 55 plate B beneath the rotating disk.

At the commencement of a game a rod or

peg bearing a number or mark distinguishing the billiard table on which the game is to be played is inserted in one of the apertures of the revolving disk A and it is so arranged that at the end of the pre-arranged interval of time for which the billiard table is engaged for the game, the rods or pegs will be conveyed over the surface of the fixed plate B to arrive at a gap b formed therein as shown in Fig. 4.

At this instant the rod or peg will drop through a chute on to the tray C. The tray is so balanced on a pivot that the added weight of the rod or peg causes it to drop 70 and make electrical contact thereby completing a circuit from batteries D through an electric bell E which forthwith commences and continues to ring until the rod or peg has been abstracted from the tray C by the attendant in charge.

It can be so arranged that the above described electric circuit is at the same time completed through a bell affixed to the billiard table on which the game is being 80 played, and the players thereby warned that the time specified for the game has expired.

A lid F may be hinged or secured in any other suitable manner to the casing of the device, and in this lid are formed a plurality of apertures f^1 , f^2 and f^3 . At the under side of the lid or cover F are slidably mounted a pair of arms f^4 and f^5 , located at opposite sides of the rotating disk A and provided with upstanding projections or pins f^8 and f^9 extending through slots in the lid F and adapted to enable the arms to be moved beneath the lid. The arms f^4 and f^5 are provided with portions normally underlying the apertures f^1 , f^2 and f^3 , to prevent pegs which 90 may be inserted into such apertures from directly entering the apertures a^1 , a^2 and a^3 of the rotating disks A, but by sliding one or the other of the arms backward by means of its operating pin, pegs which have been inserted in the apertures f^1 , f^2 and f^3 will be permitted to drop into the corresponding apertures in the rotary disk A.

Adapted to be operated by the movement of the arms f^4 and f^5 , respectively, are a pair of registering devices i^1 and i^2 . These devices are of commonly well known construction, and it is thought that further illustration and description of the details of the registering devices are unnecessary, since I 105 am making no claim to the registering devices *per se*. The registering devices are 110

shown connected with the arms f^4 and f^5 by means of wire connections j^1 and j^2 . These registering devices indicate the number of times the arms have been operated to permit 5 pins inserted in the apertures of the lid F to drop into the apertures of the rotary disk A. It is also deemed unnecessary to illustrate in detail the mechanism for rotating the disk A. This may be done by means of a clock 10 movement, as a, or any other similar device. From the construction described, it will be seen that the pegs inserted through the aperture f^1 enter the apertures a^1 in the disk A at a position angularly more distant from 15 the opening or gap b in the stationary plate B than do the pegs inserted through the aperture f^2 into the apertures a^2 and slightly less distant from the gap b of the plate B than pins inserted through the aperture f^3 20 into the apertures a^3 . Hence, the period which will elapse before the pegs in the apertures a^1 are dropped, is longer than the period which will elapse before the pegs in the apertures a^2 are dropped and slightly 25 less than the period which will elapse before the pegs in the apertures a^3 are dropped. Pegs are therefore inserted in the apertures a^1 to time games of longer duration than the pegs inserted in the aperture f^2 and of 30 slightly shorter duration than pegs inserted in the apertures f^3 . The second lid or cover G may be hinged or otherwise secured at the side of the casing where the pegs are delivered to the tray C so as to give access to such 35 tray, a glazed aperture g being preferably formed in such cover.

I claim—

1. A device of the class described including a casing, a disk mounted for rotation in

said casing and provided with a plurality of 40 annular rows of perforations, a plurality of pegs adapted to be inserted in said perforations, a lid for the casing having a plurality of perforations, one for each of said annular rows, means carried by said lid for normally 45 separating the lid perforations from the disk perforations and manually operable exteriorly of the lid to permit passage of a peg from a lid perforation to a disk perforation, and means connected with said separating 50 means for registering the operation thereof.

2. A device of the class described including a casing, a disk mounted for rotation in said casing and provided with a plurality of annular rows of perforations, a plurality of 55 pegs adapted to be inserted into said perforations, a lid for said casing having a plurality of perforations, one for each of said annular rows, means carried by the lid and arranged interiorly of the casing for normally 60 separating the lid perforations from the disk perforations, and manually operable exteriorly of the lid to permit the passage of a peg from a lid perforation to a disk perforation, means connected with the 65 separating means for registering the operation thereof, a stationary disk mounted in said casing below the rotating disk and provided with an opening through which a peg carried by the rotating disk will be permitted 70 to drop, and a tiltable receptacle pivotally mounted below the said opening and adapted to receive a peg and to be tilted by the same to complete an electrical circuit to audibly indicate the dropping of such peg. 75

In testimony whereof I have signed my name to this specification.

JOHN JEREMIAH.

Copies of this patent may be obtained for five cents each, by addressing the "Commissioner of Patents, Washington, D. C."
